F. HENSON

ATTACHMENT FOR WASHING MACHINES

Filed April 21, 1921

UNITED STATES PATENT OFFICE.

FRED HENSON, OF ST. LOUIS, MISSOURI.

ATTACHMENT FOR WASHING MACHINES.

Application filed April 21, 1921. Serial No. 463,137.

To all whom it may concern:

Be it known that I, FRED HENSON, a citizen of the United States, residing at St. Louis, in the county of St. Louis City and State of Missouri, have invented new and useful Improvements in Attachments for Washing Machines, of which the following is a specification.

This invention has reference to attachments for washing machines, and its object is to prevent the coupling of moving parts of the washing machine to the source of power until the several parts are in proper position.

15 The invention has particular reference to cylinder washing machines, in which the washing cylinder or drum is furnished with a section or lid capable of being opened for the insertion of the articles to be washed. 20 The cylinder is driven by a shaft which is removed from one end of the cylinder when it is desired to place the articles in the cylinder or to remove them therefrom and the shaft and lid are assembled with the cylinder to effect the proper rotation of the cylinder and if not so assembled damage is liable to occur.

With the invention, an obstructing device is provided to close the hole in the drive 30 axle, and the arrangement is such that the lid must be placed on the cylinder, and a locking lever must be moved up into fasteners on the lid in turn moving the shaft 35 obstructor out of obstructing position, so that the drive shaft can be pushed into gear, thus starting the cylinder. After the cylinder is started the lid cannot come open until the cylinder is stopped.

The invention will be best understood 40 from a consideration of the following detailed description, taken in connection with the accompanying drawing forming part of this specification, with the understanding, however, that the invention is not confined to any strict conformity with the showing of the drawing, but may be changed and modified so long as such changes and modifications mark no material departure from the salient features of the 45 invention as expressed in the appended claims.

In the drawing:

Fig. 1 is a perspective view of a washing machine cylinder with the lid in place and

closed and the obstructor out of the path 55 of the driving gear or shaft.

Fig. 2 is an end view of the cylinder shown in Fig. 1 with the parts in the same position.

Fig. 3 is an end view of that end of the 60 cylinder remote from the one shown in Fig. 2.

Fig. 4 is a diametric section through the hub of the cylinder showing the obstructor in position to permit the introduction of 65 the driving shaft.

Fig. 5 is a section similar to that of Fig. 4 but showing the obstructor in obstructing or interfering position.

Fig. 6 is a perspective view of the opposite 70 end of the obstructor operating lever.

Referring to the drawings, there is shown a washing machine cylinder 1, which may be taken as indicative of the general type of washing machine cylinders. The cylinder is provided with heads 2, 3, joined together by spaced longitudinal slats 4. A certain number of slats 4 included within the limits of a dotted line 5 with these slats joined together in any appropriate manner 75 comprise a lid so arranged as to be bodily removable from the cylinder in the event that it is desired to gain access to the washing machine cylinder. The cover 6 is provided near one end with latch fingers 7, 80 carried by blocks 8 or by other appropriate means, so that latch ends 9 on the ends of the fingers remote from the blocks 8 may be appropriately raised.

The cylinder 1 is provided at one end 90 with a spider 10 held to the cylinder head by screws 11 or otherwise. The head 2 carries a hub 12 with a cross piece 13 leading oppositely therefrom and made fast by screws 14 or otherwise to the head. On the 95 side of the hub 12 toward the head 2, the hub is formed with a recess 15 to accommodate one end 16 of a bail 17, said bail also having another end 18. The end 18 of the bail is radial to the head 3 and the lever end 16 is radial to the head 2, the two bail ends being joined by the intermediate portion 17 of the bail.

The end 18 of the bail 17 terminates in a pin 19 entering the head 3 parallel with 100 and close to the axis of the spider 10, and the end 16 of the bail 17 is formed with a non-circular passage 20 of a size to receive

a non-circular end 21 of a rock pin 22 fast to a rockable obstructor 23 adaptable to the outer end of the hub 12 to move into a recess 24 opening into a non-circular passage 5 25, axial to the hub 12.

The passage 25 is shown in the particular form in the drawings as of triangular shape but it is to be understood that it may be square or of any other appropriate cross 10 section, whereby a driven shaft receiving its motion from appropriate gearing, such as is employed in washing machines, may be inserted axially in the hub 12 to impart rotary motion to the cylinder 1.

15 When the bail 17 is moved to and is caught by the latches 7, the obstructor 23 is withdrawn from the passage 25, thus permitting the introduction of the drive shaft shown in Fig. 5 at 26 and provided with a triangular 20 or other shaped extension 27, depending upon the cross sectional form of the passage 25.

When it is desired to gain access to the cylinder 1, the bail 17 is withdrawn from 25 engagement with the latches 7 and moved sufficiently to release the cover 5. At the same time, the releasing movement of the bail causes the end 16 to rock the pin 22 and with it the obstructor 23, which movement 30 can only occur where the shaft 26 is moved sufficiently to carry the end 27 out of the passage 25. Under the circumstances, the bail 17 will not move toward the first position far enough to carry the obstructor 23 35 out of the path of the shaft extension 27 and consequently the cover 5 cannot be replaced, nor can the actuating mechanism of the cylinder be coupled up to the cylinder, so that the cylinder must be closed and the 40 bail 17 returned to latched position with respect to the cylinder before the actuating mechanism will again become active to the driving mechanism of the cylinder.

45 While in the drawings, the lid 5 is shown as locked in place by the bail 17 moved in one direction into engagement with the latches 7, it is to be understood that in some types of machines, the bail moves in the opposite direction to that indicated in the 50 drawings, and approaches the lid from the opposite side, requiring the location of the latches oppositely to what is illustrated. It, therefore, follows that the lid and bail may be arranged in either of two positions so far 55 as movement and locking is concerned, but, of course, the principle of operation is the same in both cases, and the following claims are to be read as broad enough to cover either of the two constructions, that is, the 60 lid and bail may be related as shown in the drawings, so that the bail moves clockwise to latch, as shown in Fig. 2, with the latches on the left hand side of the cover, or the bail and cover may be so related that the 65 bail would have to be moved counter-clock-

wise to engage and hold the cover, this being just the contrary to the showing of Fig. 2.

What is claimed is:—

1. In a washing machine, a cylinder for containing articles to be washed, an axial support for the cylinder with a non-circular passage therein, driving means for the cylinder movable into and out of the passage, and obstructing means for the driving means movable into and out of the passage. 75

2. In a washing machine, a rotatable container for the articles to be washed and provided with an axial passage of non-circular cross section, a drive shaft for the container movable into and out of the passage, and 80 obstructing means also movable into and out of the passage transversely of the direction of movement of the drive shaft with respect to the passage.

3. In a washing machine, a rotatable cylinder having an axial passage at one end to receive a drive shaft for the cylinder, a lid constituting a portion of the peripheral part of the cylinder, latch members on the lid, a bail moving in overriding relation to the lid and under the latch members to hold the lid in place, said bail having an extension disposed at the end of the cylinder, and obstructing means for the axial passage of the cylinder carried by the bail extension whereby to effectively close the passage when the bail is out of engagement with the latches on the lid. 95

4. In a washing machine, a cylinder for containing articles to be washed, a hub projecting from one end of the cylinder and provided with an axial passage, an obstructing member movable with relation to the passage into and out of obstructing relation thereto, a lid for the cylinder, a bail connected to the obstructing member and movable along the periphery of the cylinder, and latch means for the bail attached to the lid to engage or release the bail. 100

5. In a washing machine, a cylindrical 110 drum for containing articles to be washed and rotatable about a longitudinal axis, driving means adapted to be detachably connected thereto, a peripherally located lid for the drum, snap latches on the lid, a bail located on the drum and movable about the longitudinal axis thereof, said bail being movable over the lid and into and out of engagement with the latches to hold or release the lid, and means connected with the bail for preventing the connection of the drum with the driving means when the bail is out of engagement with the latches. 115

6. In a washing machine, a rotatable drum for containing articles to be washed, driving means adapted to be detachably connected thereto, said drum having a removable lid, a rockable bail supported at the ends of the drum near the axis thereof, means for holding the bail in position to re- 120 125 130

- tain the lid closed, and means connected with the bail for preventing the connection of the drum with the driving means when the bail is in position to release the lid.
- 5 7. In a washing machine, a rotatable drum for containing articles to be washed, driving means adapted to be detachably connected thereto, a peripheral lid for the drum, means for locking or releasing the lid, and
10 means connected with said last-named means and operable when the latter is in position to release the lid, to prevent the connection of the drum with the driving means.
8. In a washing machine, a rotatable drum
15 for containing articles to be washed, a lid for the drum, means for holding the lid closed or release it for opening, means for driving the drum, and means under the control of the lid holding means for preventing the con-
- nexion of the driving means to the drum 20 unless the several parts are properly positioned.
9. In a washing machine, a rotatable container, a lid for closing an opening in said container, latching means on the lid, means 25 engaging with said latching means for holding the lid in place, driving means for the container, coupling means for connecting the driving means to the container, and means actuated by said engaging means to prevent 30 the operation of the coupling means for connecting the driving means to the container when said engaging means is out of engagement with said lid latching means.

In testimony that I claim the foregoing as my own, I have hereto affixed my signature.

FRED HENSON.
